CONVERSION OF HYDROCARBONS

Lyman C. Huff, Chicago, Ill., assignor to Universal Oil Products Company, Chicago, Ill., a corporation of Delaware

Application November 30, 1936, Serial No. 113,424

17 Claims. (Cl. 196—49)

This invention particularly refers to an improved process for the selective pyrolytic conversion of four separate streams of hydrocarbon oils ranging in characteristics from low-boiling distillate such as gasoline, heavy gasoline fractions, naphtha, pressure distillate and the like to high-boiling residual oils, the light distillate stream being subjected to reforming conditions, the high-boiling residual oils being quickly heated to a high cracking temperature and thence reduced to coke in a continuous operation while the two intermediate streams are each subjected to independently controlled conversion conditions of cracking temperature and superatmospheric pressure. 15 In this invention the four selective cracking stages are correlated in an interdependent and cooperative manner so as to produce, as final products of the process, high yields of good quality gasoline and minor yields of relatively dry coke and gas of relatively high olefin content.

One of the features of the invention resides in the flexibility of operation which it provides, making the system adaptable to the treatment of a wide range of charging stocks as well as to the simultaneous treatment of a plurality of charging stocks of different characteristics. The process also possesses considerable flexibility with respect to the characteristics of the products and may, when desired, be operated for the production 30 of either relatively dry coke or good quality fuel oil as the final residual product of the process or for the simultaneous production of both coke and fuel oil residue.

While considerable importance is attached to 35 the novel cooperative relations between the various steps of the process which combine to make a new, highly desirable and advantageous cracking unit, many of its novel features are also adaptable to use in other combinations and in other 40 types of cracking systems and it is therefore not desired to limit the invention to the entire combination and sequence of steps which make up the unified system herein illustrated and described as the specific embodiment of the invention.

One of the features of the invention which is considered new, per se, comprises introducing residual liquid resulting from a separate cracking operation into a relatively low-pressure vaporizing and separating chamber to which vaporous products from a coking zone are supplied, withdrawing from the separating stage the remaining non-vaporous liquid residue, including any entrained and dissolved high-boiling materials 50 recovered from the vaporous products of the coking

operation, quickly heating these high-boiling residual liquids to a relatively high cracking temperature in a heating coil without allowing them sufficient time in the heating coil at the high conversion temperature employed to permit any substantial formation and deposition of coke therein, introducing the highly heated residual oils into the coking zone wherein they are reduced to substantially dry coke and supplying the evolved vapors to said separating zone. Although in the specific embodiment of the invention hereinafter illustrated and described, the residual liquid supplied to the low-pressure vaporizing and separating step comprises residual oil resulting from the pyrolytic conversion of lower boiling oils in separate cracking stages of the cracking system, this particular feature of the invention is not so limited since it may include as the oil supplied to the vaporizing and separating step not only cracked residue in heated state but any desired 20 hydrocarbon oil of high-boiling characteristics or relatively wide boiling range from within the system or from an external source. It may be introduced into the vaporizing and separating zone either in preheated state or otherwise, as desired, but preferably is supplied thereto at a temperature below that at which any appreciable cracking thereof will occur under the conditions employed in the vaporizing and separating zone but at a sufficiently high temperature so that by 30 commingling with the vaporous products from the coking operation it is subjected to appreciable vaporization.

Another important feature of the invention resides in the cooperative relation between the reforming and coking stages of the system whereby a regulated portion of the highly heated products from the heating coil of the reforming step are commingled with the residual materials undergoing coking to assist the coking operation while 40 the remainder of the highly heated reformed products are cooled sufficiently to prevent any excessive further cracking and polymerization thereof, undesirable high-boiling polymers and cracked products separated from the partially 45 cooled materials and returned to the coking step.

Another feature of the invention comprises subjecting vaporous products of the desired end-boiling point from the fractionating step of a cracking operation to further fractionation 50 whereby they are separated into fractionated vapors within the boiling range of the desired gasoline product of the process, which is recovered therefrom by condensation, and higher boiling components including high-boiling gasoline 55

fractions of unsatisfactory antiknock value, supplying regulated quantities of said higher boiling components to a heating coil wherein they are subjected to reforming conditions of cracking 5 temperature and substantial superatmospheric pressure, cooling at least a portion of the highly heated products discharged from the heating coil to a sufficiently low temperature to prevent their appreciable continued cracking, subjecting the 10 vaporous components of the partially cooled products to separate fractionation, subjecting fractionated vapors of the desired end-boiling point, comprising materials of gasoline boiling range from the last mentioned fractionating step, to 15 condensation, recovering the resulting distillate, returning reflux condensate formed in the last mentioned fractionating step to the first fractionating step wherefrom the vaporous conversion products subjected to said further fractionation 20 are derived and supplying reflux condensate from said first fractionating step to the cracking step wherein the first mentioned vaporous conversion products are produced.

Other advantageous features of the invention 25 which are novel in themselves and/or in combination with various other features of the process will be apparent to those familiar with the cracking art by reference to the accompanying diagrammatic drawings and the subsequent description 30 thereof.

One specific embodiment of the invention comprises subjecting relatively light and relatively heavy hydrocarbon oil cracking stocks each to a suitable independently controlled cracking 35 temperature at substantial superatmospheric pressure in independently controlled light oil and heavy oil cracking coils and an enlarged reaction zone maintained at substantial superatmospheric pressure to which heated products from both 40 cracking operations are supplied, separating the resulting vaporous and residual liquid conversion products and subjecting the latter to further vaporization at substantially reduced pressure, heating the remaining residual liquid to a high 45 cracking temperature at superatmospheric pressure in another independently controlled heating coil, introducing the heated materials into an enlarged coking zone wherein their high-boiling components are reduced to substantially dry coke, 50 separately heating another hydrocarbon oil of lower boiling characteristics than that supplied to said light oil cracking step to reforming conditions of cracking temperature and superatmospheric pressure in another independently 55 controlled heating coil, introducing a regulated portion of the heated products from the reforming step into the coking zone to commingle therein with the materials undergoing coking and assist the coking operation, cooling the remaining portion of said heated products from the reforming step sufficiently to prevent their excessive further conversion, separating from the partially cooled materials high-boiling non-vaporous 60 components, returning the latter to the heating coil to which said residual liquid is supplied, subjecting the total vaporous conversion products of the process and hydrocarbon oil charging stock for the process to fractionation for the formation of light oil and heavy oil cracking 65 stocks, supplying the same, respectively, to the light oil and heavy oil cracking steps, subjecting fractionated vapors of the desired end-boiling point to condensation and recovering the resulting distillate.

Another specific embodiment of the invention

comprises subjecting an oil of relatively high-boiling characteristics recovered from within the system to cracking temperature at superatmospheric pressure in a heating coil, simultaneously subjecting another oil of lower boiling characteristics to independently controlled conditions of pyrolytic conversion in a separate heating coil, introducing heated products from both heating coils into a reaction chamber also maintained at substantial superatmospheric pressure wherein they are subjected to appreciable continued cracking, withdrawing both vaporous and liquid conversion products in commingled state from the reaction chamber and introducing the same into a reduced pressure vaporizing and separating chamber wherein the liquid products are subjected to appreciable vaporization and the residual liquid is separated from the vapors, withdrawing the vaporous products from the vaporizing and separating chamber and subjecting the same to fractionation in commingled state with hydrocarbon oil charging stock for the process whereby the components of the commingled materials boiling above the range of the desired light distillate product of this stage of the system are condensed as reflux condensate and separated into selected relatively low-boiling and high-boiling fractions, supplying said high-boiling fractions to the first mentioned heating coil for cracking, supplying said low-boiling fractions 25 to said separate heating coil for cracking, removing from the fractionator vapors of the desired end-boiling point, including substantially all of the components of the oil supplied to the fractionator boiling within the range of gasoline, subjecting a regulated portion of said fractionated vapors to partial condensation, returning regulated quantities of the resulting distillate to the upper portion of the fractionator as a cooling and refluxing medium, subjecting the remaining portion of said fractionated vapors to further fractionation whereby they are separated into components boiling within the range of the desired gasoline product of this stage of the system and higher boiling components, which latter are condensed by said further fractionation, removing said low-boiling components from the last mentioned fractionating zone, subjecting the same to partial condensation, returning regulated quantities of the resulting distillate to the last mentioned fractionating zone as a cooling and refluxing medium, subjecting the uncondensed materials and any excess distillate from both of said partial condensation steps to further cooling and condensation, recovering and separating the resulting distillate and uncondensed gases, withdrawing said condensate formed in the last mentioned fractionating zone therefrom, returning a regulated portion thereof to the first mentioned fractionating zone, supplying another portion of the condensate in regulated quantities to a separate heating coil wherein it is subjected to reforming conditions of cracking temperature and substantial superatmospheric pressure, introducing regulated quantities of the resulting highly heated products into a coking zone wherein they commingle with heated residual liquids supplied thereto from within the system, as subsequently described, whereby to assist reduction of said residual liquids to coke, cooling the remaining portion of the highly heated products from the last mentioned heating coil sufficiently to prevent their excessive further cracking, introducing the partially cooled materials and vaporous products removed from the coking zone into another sep- 75

arating chamber wherein the high-boiling non-vaporous components of the materials supplied thereto are separated from the vapors, removing said residual liquid from the first mentioned vaporizing and separating chamber and supplying at least a regulated portion thereof to the last mentioned separating chamber, withdrawing the resultant commingled high-boiling liquids from the last mentioned separating chamber, supplying the same to another separate heating coil wherein they are quickly heated to a relatively high cracking temperature, introducing the heated materials from the last mentioned heating coil into the coking zone wherein their high-boiling components are reduced to substantially dry coke, subjecting vaporous products from the last mentioned separating chamber to fractionation in another fractionating zone for the formation of reflux condensate, passing regulated quantities of the last mentioned reflux condensate in indirect heat exchange with said condensate supplied to the reforming coil whereby to supply additional heat to the latter, prior to its introduction into the reforming coil and whereby to partially cool said reflux condensate, returning reflux condensate from the last mentioned fractionating zone to the first mentioned fractionating zone, subjecting fractionated vapors of the desired end-boiling point from said last mentioned fractionating zone to partial condensation, returning regulated quantities of the resulting distillate to the upper portion of said last mentioned fractionating zone as a cooling and refluxing medium, subjecting uncondensed materials and any excess distillate from the last mentioned partial condensation step to further cooling and condensation and recovering and separating the resulting distillate and uncondensed gases.

The accompanying diagrammatic drawings (Figs. 1 and 2) illustrate one specific form of apparatus embodying the features of the invention and in which the process may be conducted as outlined in the following description of the drawings.

Referring to the drawings, relatively high-boiling charging stock or charging stock of relatively wide boiling range is supplied through line 1 and valve 2 to pump 3 wherefrom it is directed through line 4 and may be supplied through valve 5 in this line to fractionator 6.

Low-boiling charging stock such as distillate, naphtha, gasoline or the like is supplied through line 7 and valve 8 to pump 9 wherefrom it is directed through line 10, valve 11, heat exchanger 12, line 13 and valve 14 into fractionator 6.

The oil passed through heat exchanger 12 is indirectly contacted with relatively hot vaporous products undergoing fractionation in this zone whereby it is preheated and serves to partially cool the vapors and assist their vaporization.

The oils supplied, as described, through lines 4 and 13 into fractionator 6 directly commingle in this zone with the hot vaporous products undergoing fractionation whereby said oils are subjected to appreciable vaporization and to fractionation, together with the vaporous conversion products and also serve to partially cool the vapors and assist fractionation in this zone.

The condensate removed from the vaporous products by fractionation in fractionator 6 including components of both in the charging stock and the vaporous conversion products supplied to this zone boiling above the range of gasoline is separated into light and heavy fractions of se-

lected boiling characteristics. The high-boiling fractions of heavy reflux condensate is withdrawn from the lower portion of the fractionator and directed through line 15 and valve 16 to pump 17 by means of which it is fed through line 18 and valve 19 to cracking coil 20.

Coil 20 is located within a suitable furnace 21 and the oil passing through the coil is heated to the desired cracking temperature, preferably at a substantial superatmospheric pressure. The heated products are discharged from coil 20 through line 22 and valve 23 into reaction chamber 24, preferably entering the upper portion of this zone and being directed by means of a suitable spreader flange or spray arrangement such as indicated, for example, at 25 against the inner surface of the walls of the chamber.

The light or low-boiling reflux condensate formed in fractionator 6 is withdrawn from a suitable intermediate point in the fractionator and directed through line 26 and valve 27 to pump 28 by means of which it is directed through line 29 and valve 30 into cracking coil 31.

A suitable furnace 32 supplies the required heat to the oil passing through coil 31 to subject the same to the desired cracking temperature which is preferably higher than that employed in heating coil 20, preferably at a substantial superatmospheric pressure. The heated products are discharged from coil 31 through line 33 and may be directed, all or in part, through line 34 and valve 35 in reaction chamber 24.

Chamber 24 is also preferably maintained at a substantial superatmospheric pressure and, although not indicated in the drawings, is preferably well insulated to prevent the excessive loss of heat therefrom by radiation. The heated products supplied to chamber 24 are thereby subjected to appreciable continued conversion time in this zone and both vaporous and liquid conversion products are withdrawn in commingled state from the lower portion of the chamber and directed through line 36 and valve 37 into vaporizing chamber 38.

Chamber 38 is preferably operated at a substantially reduced pressure relative to that employed in the reaction chamber by means of which appreciable further vaporization of the liquid products supplied to this zone is accomplished. The oils remaining unvaporized in chamber 38 are withdrawn from the lower portion of this zone through line 39 and valve 40 to pump 41 wherefrom they are directed through line 42, valve 43 and line 44 into the lower portion of column 45, the purpose of which will be later described.

Vaporous products are directed from the upper portion of chamber 38 through line 46 and valve 47 into fractionator 6 wherein they commingle with the charging stock supplied to this zone, as previously described, and are subjected therewith to fractionation for the formation of said light and heavy reflux condensates and for the recovery therefrom of low-boiling fractions comprising materials within the boiling range of gasoline.

Fractionated vapors of the desired end-boiling point comprising materials within the boiling range of the desired final gasoline product of the process as well as, when desired, somewhat higher boiling fractions, are removed from the upper portion of fractionator 6 through line 48 and these products are divided into two streams, one of which passes from line 48 through line 50 and valve 51 into fractionator 52 for separation therein into light and heavy fractions, as will be later

described, while the other stream passes through valve 49 in line 48 to condensation and cooling in condenser 53. The resulting distillate and uncondensed materials pass through line 54 and valve 55 into accumulator 56 and distillate is returned from this zone by means of line 57, valve 58, pump 59, line 60 and valve 61 to the upper portion of fractionator 6 wherein it serves as a cooling and refluxing medium. Gas and uncondensed vapors are directed from accumulator 56 through line 62 and valve 63 to sub-coolers 64, the purpose of which will be later described.

The vapors supplied, as previously described, from fractionator 6 to fractionator 52 are subjected to additional fractionation in the latter zone whereby their components, within the boiling range of gasoline, or more particularly low-boiling gasoline fractions, are recovered from their higher boiling components. The low boiling fractions are removed from the upper portion of fractionator 52 and directed through line 65 and valve 66 to cooling and partial condensation in condenser 67. The resulting distillate and uncondensed vapors and gases are directed through line 68 and valve 69 to accumulator 70. Distillate is returned from accumulator 70 by means of line 71, valve 72, pump 73, line 74 and valve 75 to the upper portion of fractionator 52 to serve as a cooling and refluxing medium in this zone. Uncondensed vapors and gases as well as any condensate recovered in receiver 70 in excess of that required as a cooling and refluxing medium are directed through line 76 and valve 77 into line 62 wherein they commingle with similar materials from receiver 56, being directed therewith, as previously described, to sub-coolers 64.

The materials thus supplied to sub-coolers 64 comprise gaseous products of the cracking operation, previously described, and other components of the vaporous products from fractionator 6 which boil within the range of gasoline and are of satisfactory antiknock value. The sub-cooling accomplished in zone 64 serves to effect separation in receiver 80 to which the sub-cooled products are supplied through line 78 and valve 79 of normally condensable components from uncondensed gases. The former comprising the distillate collected in receiver 80 is withdrawn therefrom as the final product of the process through line 81 and valve 82 to storage or elsewhere, as desired. The normally gaseous products are released from receiver 80 through line 83 and valve 84.

High-boiling components of the vaporous products supplied to fractionator 52 which are condensed in this zone and which comprise, for example, high-boiling motor fuel fractions of unsatisfactory antiknock value and which may include, when desired, somewhat higher boiling materials such as heavy naphtha fractions, pressure distillate bottoms or the like are withdrawn from the lower portion of fractionator 52 and may be directed through line 85 and valve 86 to pump 87 by means of which they are supplied, as will be later described, to further treatment within the system for the improvement of their motor fuel characteristics, particularly with respect to antiknock value. It is also within the scope of the invention to remove a regulated portion or all of the material withdrawn from the bottom of fractionator 52 from the system. This is accomplished by diverting the same from a line 88 through line 89, line 89 and valve 90 to cooler 91 wherefrom the cooled product is discharged through line 92, line 93 and valve 95 to storage

or to any desired further treatment. This method of operation is particularly advantageous in case the high-boiling components of the gasoline product of this state of the system are of satisfactory antiknock value but may be advantageously subjected to different treatment than the low-boiling gasoline fractions such as, for example, chemical treatment for the reduction of sulphur content and the like, clay treatment for the reduction of gums or in case the low-boiling fractions require stabilization and it is not necessary to subject the high-boiling fractions to such treatment.

It is also within the scope of the invention to utilize regulated quantities of the oil withdrawn from the lower portion of fractionator 52 as a cooling and refluxing medium in fractionator 6, in which case oil from the bottom of fractionator 52 may be passed through valve 96 in line 88 to pump 97 by means of which it is supplied through line 98 and valve 99 to heat exchanger 12 and thence through line 13 and valve 14 into fractionator 6.

Provision is also made for returning a regulated portion or all of the cooled oil from cooler 91 to fractionator 6 by means of directing the same through valve 100 in line 92 into line 88 and thence in the manner previously described, to pump 97, heat exchanger 12 and fractionator 6. The invention also contemplates returning distillate from receiver 70 to fractionator 6 by diverting regulated quantities thereof from line 74 through line 101 and valve 102 into line 98 and thence, as previously described, through heat exchanger 12 into fractionator 6.

Provision is also made for returning regulated quantities of the bottoms from fractionator 52 to the lower portion of this zone in order to assist cooling therein by means of diverting the oil preferably after it is passed through cooler 91, as previously described, from line 98 through line 103 and valve 104 into the lower portion of fractionator 52.

Line 105 and valve 106 communicating with line 88 is provided for the purpose of supplying distillate from an external source to pump 97 and thence either to the lower portion of fractionator 52 or through heat exchanger 12 to fractionator 6, in the manner previously described. This additional cooling medium may comprise any desired oil from an external source which will not contaminate the products of the process with which it is commingled or it may comprise oil from the lower portion of fractionator 52 previously supplied to storage, in the manner already indicated.

When the material withdrawn from the lower portion of fractionator 52 comprises gasoline fractions and/or somewhat higher boiling materials of the nature previously mentioned which may be advantageously subjected to additional cracking or reforming to produce additional yields of gasoline of good antiknock value, a portion or all of this material is supplied, as previously described, to pump 87 wherefrom it is fed through line 107 and valve 108 and this material may either be directed, all or in part, through valve 109 in line 107 to cracking or reforming coil 110 or it may first be preheated by diverting it, all or in part, from line 107 through line 111, 70 through branch lines 112 controlled by valves 113 into heat exchanger 114 wherein it passes in indirect heat exchange with relatively hot intermediate products of the process supplied to the heat exchanger, as will be later described, and 75

wherefrom the preheated oil is directed through lines 115 and valves 116 into line 117 and thence through line 107 to coil 110.

Coil 110 is located within a suitable furnace 118 by means of which sufficient heat is supplied to the oil passing therethrough to subject it to the desired conversion conditions of relatively high cracking temperature, preferably at a relatively high superatmospheric pressure. Preferably the oil passing through coil 110 is subjected to a more prolonged conversion time than that employed for the higher boiling oils separately subjected to cracking within the system and for this purpose, although a conventional heating coil and furnace are shown in the drawings, any of the well known types of heaters wherein a soaking section is provided is preferably employed.

The highly heated products are discharged from heating coil 110 through line 119 and may be directed, all or in part, through valve 120 in this line to fractionator 121 or a portion or all of these materials may be diverted from line 119 and supplied through line 122, valve 123, line 124, valve 125 and line 126 into fractionator 6 wherein they commingle with the vaporous products supplied to this zone, as previously described, from chamber 38 and are subjected to fractionation therewith, in the manner previously described.

When products from coil 110 are supplied, as described, to fractionator 121 they are separately subjected to fractionation in this zone and separated into components boiling within and above the boiling range of the desired final gasoline product. The high-boiling fractions, including any residual liquid conversion products and/or heavy polymers, are withdrawn from the lower portion of fractionator 121 through line 127 and may, when desired, be removed, all or in part, from the system through line 128 and valve 129 to cooling and storage or elsewhere, as desired, or this material may be directed, all or in part, through valve 130 in line 127 to pump 131 by means of which it is directed through line 132, valve 133 and line 44 into separating and fractionating column 45 wherein it is subjected to further treatment, as will be later described.

When desired, intermediate fractions of the materials supplied to fractionator 121 comprising their components boiling above the range of the desired gasoline product and below the range of the relatively heavy liquids which it is desired to subject to further treatment in column 45 may be removed from a suitable intermediate point in fractionator 121 and directed through line 134 and valve 135 to pump 136 by means of which they are supplied through line 137 and valve 138 to cooler 139 and thence through line 140, valve 141, line 124, valve 125 and line 126 into fractionator 6 to commingle therein with the other materials supplied to this zone, as previously described, and be subjected to fractionation therewith.

Fractionated vapors of the desired end-boiling point comprising normally gaseous products and materials within the boiling range of the desired gasoline product are directed from the upper portion of fractionator 121 through line 144 and valve 145 to cooling and partial condensation in condenser 146. The resulting distillate and uncondensed vapors and gases pass through line 147 and valve 148 to accumulator 149. Distillate is recirculated from accumulator 149 by means of line 150, valve 151, pump 152, line 153 and valve 154 to the upper portion of fractionator 121 to serve as a cooling and refluxing medium in this

zone. Any additional distillate collected in receiver 149 is directed together with uncondensed vapors and gases from this zone through line 155, valve 156 and line 157 to sub-cooler 158 wherein additional cooling to effect condensation of the vaporous products within the boiling range of the desired gasoline product is accomplished. The resulting distillate and uncondensed gases pass through line 159 and valve 160 to receiver 161 wherein separation of the distillate and gases is accomplished. Gaseous products are released from receiver 161 through line 162 and valve 163 and distillate is withdrawn from this zone through line 164 and valve 165 to storage or to any desired further treatment.

The heavy oils supplied to column 45 from chamber 38 and when this method of operation is employed from the lower portion of fractionator 121 may be subjected to additional vaporization in the lower portion of column 45 for the recovery of desirable low-boiling fractions therefrom. The remaining residual liquids are removed from the lower portion of column 45 and directed through line 166 and valve 167 to pump 168 by means of which they are supplied through line 169 and valve 170 to further treatment in heating coil 171.

A suitable furnace 172 supplies the required heat to the heavy oils passing through coil 171 to quickly heat the same preferably to a relatively high temperature sufficient to induce or assist their subsequent reduction to coke without allowing the oil to remain in the heating coil and communicating lines for a sufficient length of time to permit excessive coke formation and deposition therein. The heated residual oils are discharged from heating coil 171 through line 173 and valve 174 and are split by means of stream-divider 175 into two streams of substantially equal volume which are directed through the respective lines 176 and 176' into coking chambers 177 and 177'. The heated residual oil may enter the coking chambers at any desired point or plurality of points therein, provision being made in the case here illustrated for supplying the heated oil from line 176 through line 178 and valve 179 into the upper portion of chamber 177 or through line 180 and valve 181 into the lower portion of the chamber while the stream of heated oil from line 176' may pass through line 178' and valve 179' into the upper portion of chamber 177 or through line 180' and valve 181' into the lower portion of the chamber or heated products may be supplied into both the upper and lower portions of the coking chambers by means of the lines and valves described.

The heated residual oils supplied to the coking chambers are reduced therein to substantially dry coke and preferably in order to assist the coking operation and to reduce the volatility of the coke produced regulated quantities of the highly heated relatively low-boiling oils from coil 31 and/or from coil 110 may be introduced into the coking zones wherein they preferably come into direct contact with the materials undergoing coking therein and pass upwardly therethrough to supply additional heat to the materials undergoing coking and further assist the coking operation by their partial pressure effect. Provision is made for diverting from line 33 a regulated portion or all of the heated products discharged from coil 31 into line 182 wherefrom they are directed through valve 183 in this line and through lines 184 and 184' controlled, respectively, by valves 185 and 185' into the lower por-

tion of coking chambers 177 and 177', respectively. Provision is also made in the case here illustrated, for diverting a regulated portion or all of the highly heated products discharged from 5 coil 110 through line 119 into line 186 and thence through valve 187 in this line into line 183 and thence, as previously described, into the lower portion of coking chambers 177 and 177'.

The coke produced in the coking chambers may 10 be allowed to accumulate therein until they are substantially filled or until their operation is completed for any other reason, following which the chambers may be cleaned in any well known manner, not illustrated, and prepared for further 15 operation.

It will, of course, be understood that although two coking chambers are shown in the drawings, a single coking zone or more than two such zones may be employed, when desired. When a plurality of coking zones is utilized either alternate 20 or simultaneous operation thereof may be employed, alternate operation being preferred in order that the coking stage in common with the rest of the system may be operated continuously.

25 The provisions for introducing heated products from coil 31 and/or coil 110 into the coking zone, in addition to assisting the coking operation in the manner above described, permits pre-heating the coking chambers before the residual oil to be coked is supplied thereto.

30 Coking chambers 177 and 177' are provided, respectively, with drain-lines 188 and 188' having the respective valves 189 and 189'. These lines and valves may also be utilized as a means of introducing suitable cooling materials such as water, steam or the like into the mass of coke accumulated in the chambers after their operation is completed and preferably after they have been isolated from the system in order to hasten 40 cooling and facilitate removal of the coke.

Vaporous products are withdrawn from the upper portion of chambers 177 and 177' through the respective lines 190 and 190' having the 45 respective shut-off valves 191 and 191' through a stream uniting valve 192 into line 193 wherefrom they are directed into the lower portion of column 45.

The materials supplied to column 45 are separated by vaporization and fractionation into 50 three components, the heavy components comprising materials withdrawn from the lower portion of the column and returned, as previously described, to coil 171 include any heavy residual liquids, tars and the like of high coke-forming 55 characteristics carried over with the vapors from the coking zone and also include non-vaporous residual components of the liquid products supplied to column 45, as previously described, from chamber 38 and fractionator 121.

60 The intermediate components of the materials supplied to column 45 comprise the fractions of these materials, suitable for further cracking which boil above the end-point of the desired final light distillate product of this stage of the 65 system and below the initial boiling point of the materials returned to heating coil 171. These intermediate fractions are withdrawn from a suitable intermediate point in column 45 and are directed through line 194 and valve 195 to pump 70 196 wherefrom they are fed through line 197 and may be directed, all or in part, through line 126 and valves 198 and 199 into fractionator 6 to commingle therein with the other materials undergoing vaporization and fractionation in this 75 zone and be subjected to fractionation therewith.

Preferably, however, in order to recover useful heat from the intermediate products thus withdrawn from column 45 and to partially cool the same so that they may, in turn, partially cool and assist fractionation of the vaporous products in fractionator 6 when returned to this zone, all or a portion of the intermediate products may, when desired, be directed from line 197 through line 200 and through branch lines 201 containing valves 202 into and through heat exchanger 114 16 wherein they pass in indirect heat exchange with the relatively cool oil passing from the lower portion of fractionator 52 to coil 110, in the manner previously described. The thus cooled intermediate fractions pass from heat exchanger 114 15 through lines 203 containing valves 204 into line 205 from which they are directed into line 126 and thence to fractionator 6.

Provision is also made for supplying a regulated portion or all of the intermediate products 20 from column 45 to further cracking in coil 110 by means of diverting the same from line 200 through line 206 and valve 207 into line 107 and thence to heating coil 110. This method of operation permits selectively cracking the intermediate products of the coking stage of the system 25 separate from the light and heavy fractions of the reflux condensate produced in the first described cracking operations and is particularly desirable in case the gasoline produced in said 30 first mentioned cracking operations is of satisfactory antiknock value and the high-boiling fractions of said gasoline do not require reforming in heating coil 110. However, it is entirely within the scope of the invention to supply both 35 relatively light distillate, including any heavy gasoline fractions, from fractionator 52 and higher boiling intermediate fractions from column 45 both to heating coil 110 and subject the commingled materials to relatively severe crack- 40 ing conditions in this zone.

Provision is made in the case here illustrated, for supplying a regulated portion or all of the products discharged from heating coil 110 to column 45, when desired, this being accomplished 45 by means of line 238 containing valve 209 which communicated with line 119 and with the lower portion of column 45.

Provision is also made, in the case here illustrated, for supplying a regulated portion or all 50 of the relatively heavy charging stock to column 45 by diverting said charging stock from line 4 through line 210 and valve 211 wherefrom it may be directed through either or both of the branch lines 212 and 213 containing valves 214 55 and 215, respectively, into the respective lines 216 and 217 and thence into column 45. Line 216 enters column 45 below the point at which intermediate fractions are withdrawn from this zone and line 217 enters the column above this point. 60

Provision is also made for returning intermediate fractions withdrawn from column 45 back to this zone in regulated quantities preferably after being cooled in heat exchanger 114 whereby to serve as a cooling and fractionating medium 65 in column 45. This is accomplished by means of valves 218 and 219 in the respective lines 216 and 217, each of which communicate with line 126 and with column 45.

The overhead vaporous product from column 70 45 comprising materials within the boiling range of the final gasoline product of this stage of the process are directed from the upper portion of column 45 through line 220 and valve 221 to condenser 222 wherein they are subjected to cooling 75

and partial condensation. The resulting distillate and uncondensed vapors and gases pass through line 223 and valve 224 into accumulator 225 wherefrom regulated quantities of the distillate may be recirculated by means of line 226, valve 227, pump 228, line 229 and valve 230 back to the upper portion of column 45 to serve as a cooling and refluxing medium in this zone. Uncondensed vapors and gaseous products pass together with any excess of condensate recovered in accumulator 225 from this zone through line 231 and valve 232 into line 157 wherein they commingle with similar materials from accumulator 149, passing therewith to further cooling and condensation in sub-cooler 158 and thence to separation in receiver 161, as previously described.

In addition to the methods and means of cooling and heat exchange, previously described, provision is made for controlled cooling to any desired degree of various relatively hot intermediate products of the process at various points in the system by directly commingling the same with cooler intermediate products. For example, it may be desirable to partially cool the relatively hot products supplied from coil 31 to chamber 24 and/or to cool the conversion products from the lower portion of chamber 24. This is accomplished, in the case here illustrated, by diverting regulated quantities of the low-boiling reflux condensate removed from fractionator 6 from line 26 through line 233 and valve 234 to pump 235 wherefrom it is directed through line 236 and may pass, all or in part, through valve 237 in this line into line 238 and thence through lines 239 and 240 into line 34, entering line 34 in the case here illustrated, at valve 35 in this line through valve 241 in line 240. Preferably, however, a portion or all of the light reflux thus diverted from line 27 is passed through cooler 236 before it is utilized as a cooling medium, this being accomplished by means of diverting the same from line 236 through line 242 and valve 243 into cooler 244 and thence through line 245 and valve 246 into line 238. This low-boiling reflux condensate with or without first passing through cooler 244 may also be introduced, when desired, into the lower portion of chamber 24 through line 247 and valve 248 and it may also be utilized, when desired, as a means of partially cooling the hot products discharged from coil 171 by diverting it from line 239 through line 249 and valve 250 into line 251 and thence through valve 252 into line 173. Provision is also made in the case here illustrated, for introducing light reflux from fractionator 6 from line 251 through line 253 and valve 254 into line 197 wherein it commingles with the intermediate fractions withdrawn from column 45 and is subjected to further treatment therewith and/or for passing said light reflux in regulated quantities through valve 255 in line 251 into line 137 wherein it commingles with the intermediate fractions withdrawn from fractionator 121 and is subjected to further treatment therewith.

It is also often desirable to partially cool the highly heated products discharged from coil 110, particularly in case a portion or all of these materials are supplied to column 45 and/or to fractionator 121. The cooling medium utilized for this purpose, in the case here illustrated, comprises a selected low-boiling fraction of the vaporous products undergoing fractionation in column 45. This selected low-boiling fraction is withdrawn from a suitable point in the upper

portion of column 45 and directed through line 256 and valve 257 to pump 258 wherefrom it is directed through line 259 and may pass thence either, all or in part, through cooler 260 by means of lines 261 and 263 controlled by the respective valves 262 and 264 or directly from line 259 through line 265 and valve 266 into line 267 wherefrom it is introduced into line 119 commingling therein with the heated products supplied from coil 110 to column 45 and/or to fractionator 121.

Provision is also made for partially cooling the vaporous products withdrawn from the coking zone, particularly for the purpose of preventing the formation and accumulation of coke deposits in this line and in the valves interposed therein. Provision is therefore made for introducing suitable cooling oil into valves 191 and 191' or into the streams of vaporous products in lines 190 and 190' ahead of these valves, this being accomplished by means of line 268 and branch lines 269 controlled by valves 270. The cooling oil employed for this purpose may comprise, for example, regulated portions of the condensate from fractionator 45, preferably after it is passed through heat exchanger 114, although well known means for supplying this cooled condensate to line 268 are not shown in the drawing.

It will, of course, be understood that any other suitable cooling material may be utilized at the points mentioned and that similar means may be employed for cooling at any other desired points in the system.

Provision is also made for using steam, when desired, in fractionator 6 and column 45 to which it may be supplied through the respective lines 271 and 273 controlled, respectively, by valves 272 and 274. The steam thus utilized commingles with the steam undergoing fractionation, assisting their fractionation and exerting a refining action thereon.

In addition to the provisions comprising lines 128 and valve 129 for removing condensate from fractionator 121 as a final product of the process, any of the various other intermediate products of the system may be withdrawn therefrom in a similar manner. For example, a portion or all of the low-boiling reflux condensate from fractionator 6 may be removed from the system by passing the same through valve 275 in line 238, preferably after it has passed through cooler 244. Intermediate components of the materials supplied to column 45 may also be withdrawn from the system to cooling and storage or elsewhere, as desired, by diverting the same from line 126 through line 276 controlled by valve 277. The oils thus withdrawn from column 45, fractionators 121 and fractionator 6 may comprise, for example, materials suitable as domestic fuel or as Diesel fuel and in accordance with the process of the invention, regulated quantities of such materials may be produced to meet market requirements in addition to producing good quality gasoline, liquid residue, coke and gas, the production of all of these materials being correlated to suit the particular economic conditions. Under the conditions ordinarily prevailing in most localities, however, the process is preferably operated for the production of maximum yields of good quality gasoline with minimum yields of coke and gas.

The preferred range of operating conditions which may be employed to accomplish the desired results in an apparatus such as illustrated and above described are approximately as follows:

The heating coil to which heavy reflux condens-

sate from the first cracking step is supplied may employ an outlet conversion temperature ranging, for example, from 850 to 950° F., preferably with a superatmospheric pressure at this point in the system of from 100 to 500 pounds, or more, per sq. in. Substantially the same or a somewhat lower superatmospheric pressure is preferred in the succeeding reaction chamber and the communicating separating chamber may be maintained at substantially the same or preferably at 5 a somewhat lower superatmospheric pressure than that employed in the reaction chamber ranging, for example, from 200 pounds to 50 pounds, or thereabouts, per sq. in. The fractionator to which 10 vaporous products from said separating chamber 15 are supplied is preferably operated at substantially the same pressure as the separating chamber, although the pressure in the fractionator may be reduced, when desired. The heating coil to which 20 low-boiling reflux condensate from the first cracking stage is supplied may employ an outlet conversion temperature ranging, for example, from 900 to 1000° F. and preferably a superatmospheric pressure ranging from 200 to 800 pounds, 25 or more, per sq. in. is employed at the outlet from this zone. When a secondary fractionator is employed in the first cracking stage of the system the pressure employed therein may be substantially 30 equalized but, preferably, is substantially reduced relative to that employed in the preceding fractionator, the preferred range being from substantially atmospheric to 150 pounds, or thereabouts, per sq. in. superatmospheric pressure. The heating coil to which the residual liquid to be 35 coked is supplied preferably employs an outlet conversion temperature ranging from 900 to 1000° F. with a superatmospheric pressure at the outlet from this zone ranging from 50 to 200 pounds, or thereabouts, per sq. in. The oil velocity and 40 rate of heating in this coil is such that the heavy residual liquid may be heated to a sufficiently high temperature to effect its subsequent reduction to coke without excessive coke formation and deposition in the heating coil and communicating lines. 45 The coking chambers may be operated at any desired pressure ranging from substantially atmospheric up to substantially the same pressure as that employed in the residual liquid heating coil. The separating and fractionating column to which vaporous products from the coking zone are 50 supplied is preferably operated at a substantially reduced pressure relative to that employed in the first separating chamber, this pressure ranging, for example, from substantially atmospheric up to substantially the same pressure as that employed in the coking zone. When a separate 55 heating coil is employed for the reforming of high-boiling gasoline fractions from the secondary fractionator of the first cracking stage and/or for cracking intermediate products from the 60 separating and fractionating column to which vaporous products from the coking zone are supplied, this coil may utilize an outlet conversion temperature ranging, for example, from 900 to 1050° F., preferably with a superatmospheric pressure at this point in the system of from 100 to 1000 pounds, or more, per sq. in. When all or a portion of the products from the last mentioned heating coil are supplied to a separate fractionating column and/or to the same separating and fractionating column to which vaporous products from the coking zone are supplied, they are preferably cooled, prior to their introduction thereto to a temperature of from 650 to 850° F., or thereabouts, this cooling normally being accomplished 70 75

partially by pressure reduction and partially by the introduction of a suitable cooling medium into the stream of heated products. Said separate fractionating column, when employed, may be operated at any desired pressure ranging from substantially atmospheric up to substantially the same as that employed at the outlet from the last mentioned heating coil, the preferred range being from 50 to 150 pounds, or thereabouts, per sq. in. superatmospheric pressure. The condensing, 10 cooling and collecting portions of the system may be operated at any desired pressure ranging from substantially atmospheric up to substantially the same as that employed in the preceding equipment. 15

As an example of one specific method of operation of the process, the conditions employed at various points in the system and the results obtained, two charging stocks are employed. The heavy charging stock, which comprises approximately 50 per cent of the total, is a mixture of West Texas and Mid-Continent topped crude of approximately 22° A. P. I. gravity having an initial boiling point of approximately 504° F. and an end-boiling point of approximately 750° F. 20 The secondary charging stock comprises pressure distillate from other cracking units having an initial boiling point of approximately 102° F., an end-boiling point of approximately 640° F. and containing approximately 60 percent of material boiling up to 400° F. Both of these charging stocks are supplied to the primary fractionator of the first cracking stage wherefrom the overhead vapor stream, comprising the components of the pressure distillate and the components of the 25 vaporous conversion products supplied to this zone boiling up to approximately 400° F., are supplied, in part, to a secondary fractionator while another regulated quantity of these overhead vapors are subjected to partial condensation to form a condensate which is returned in regulated quantities to the primary fractionator to serve as a cooling and refluxing medium. The higher boiling components of the materials supplied to the primary fractionator are separated into relatively 30 low-boiling and high-boiling reflux condensates. 35

The high-boiling reflux condensate has an initial boiling point of about 300° F., contains approximately 40% of material boiling up to 600° F. and has a gravity of approximately 15° A. P. I. 40 This material is subjected to cracking in a heating coil, the oil entering the heating coil at a temperature of approximately 745° F. and a superatmospheric pressure of approximately 450 pounds per sq. in. and being discharged therefrom at a temperature of approximately 915° F. and a superatmospheric pressure of approximately 290 pounds per sq. in. The heated products from this coil are discharged into a reaction chamber which is maintained at substantially the same pressure 45 at that employed at the outlet from the heating coil. Both vaporous and liquid conversion products are withdrawn from the lower portion of the reaction chamber in commingled state, and introduced into a primary vaporizing and separating chamber at a temperature of approximately 365° F., this temperature being obtained partially by directly commingling a suitable cooling oil with these products and partially by pressure reduction. The primary vaporizing and separating 50 chamber is operated at a superatmospheric pressure of approximately 120 pounds per sq. in. and except for friction and loss of pressure head this pressure is substantially equalized in the succeeding fractionating, condensing and collecting por- 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

tions of this stage of the system, vaporous products from said vaporizing and separating chamber being supplied to the aforementioned fractionator to which said charging stocks are supplied and liquid products from the primary separating chamber being supplied to the same separating and fractionating column to which vaporous products from the coking stage of the system are introduced.

10 Low-boiling reflux condensate from the fractionator to which the charging stocks are supplied has an initial boiling point of about 250° F., an end-boiling point of approximately 625° F. and a gravity of about 23° A. P. I. This material is directed to a separate cracking coil, entering this zone at a temperature of approximately 680° F. and a superatmospheric pressure of approximately 760 pounds per sq. in. and being discharged therefrom at a temperature of approximately 20 955° F. and a superatmospheric pressure of approximately 290 pounds per sq. in.

Residual liquid from the primary vaporizing and separating chamber is supplied, as previously mentioned, to the separating and fractionating column to which vaporous products from the coking zone are supplied and the nonvaporous residue from the latter zone is directed to a separate heating coil wherein it is quickly heated to an outlet conversion temperature of approximately 30 950° F. at a superatmospheric pressure of approximately 115 pounds per sq. in. The heated products from this coil are introduced into alternately operated preconditioned coking chambers wherein their non-vaporous components are reduced to substantially dry coke. The coking chambers are operated at a superatmospheric pressure of approximately 115 pounds per sq. in. Vaporous products leave the coking chambers at a temperature of approximately 885° F., are partially cooled by the introduction of a suitable cooling oil and thence introduced into said separating and fractionating column.

Materials within the boiling range of the desired gasoline product are recovered from the 45 fractionated vapors removed from the fractionating zone of the coking stage, the vapors first being partially cooled and condensed to form a condensate which is utilized as refluxing medium in the fractionator and the remaining materials 50 being subjected to sub-cooling and recovered as a final distillate and a gaseous product.

A relatively heavy condensate, comprising intermediate fractions of the materials supplied to the separating and fractionating column of 55 the coking stage of the system and which have an initial boiling point of approximately 366° F., an end boiling point of about 650° F. and a gravity of about 19° A. P. I., is withdrawn from this zone and supplied to the previously mentioned 60 secondary fractionator of the first described cracking stage of the system, wherefrom at least a substantial portion of these relatively high boiling fractions are supplied to the high temperature heating or reforming coil of the system together 65 with selected high boiling fractions of the vaporous products supplied to this secondary fractionator, as previously mentioned, from the preceding fractionator.

The commingled materials supplied from the 70 secondary fractionator to the reforming coil have an initial boiling point of approximately 227° F., an end-boiling point of about 680° F. and a gravity of about 23° A. P. I. They are supplied to this zone at a temperature of approximately 550° 75 F. and a superatmospheric pressure of approxi-

mately 790 pounds per sq. in. and are discharged therefrom at a temperature of approximately 960° F. and a superatmospheric pressure of approximately 130 pounds per sq. in. The total products discharged from the last mentioned heating coil are cooled partially by pressure reduction and partially by the injection of a suitable cooling oil to a temperature of approximately 720° F. and are introduced into a separate fractionating column maintained at a superatmospheric pressure of approximately 120 pounds per sq. in. The mixture of reflux condensate, residual liquids and heavy polymerization products having a boiling range of approximately 370° F. to 734° F. are directed from the lower portion of this fractionating column to the lower portion of the separating and fractionating column of the coking stage wherefrom their heavy non-vaporous components are supplied to the heating coil of the coking stage.

Intermediate components of the products from the reforming coil, having an initial boiling point of about 166° F. and an end boiling point of approximately 616° F., are withdrawn as a side-stream from the fractionating column to which 25 these materials are supplied and returned to the previously mentioned secondary fractionator.

The overhead vaporous products from this secondary fractionator, including gasoline having an end boiling point of about 390° F. and normally 30 gaseous products, are partially cooled to form a refluxing medium for the secondary fractionator and their remaining components are subjected to further cooling, condensation and separation for the recovery of a final gasoline product and gas. 35

Overhead vaporous products from the fractionating column of the reforming stage are subjected to partial condensation for the recovery of distillate which is returned to the upper portion of said fractionating column as a cooling and refluxing medium and the remaining materials are subjected to sub-cooling and subsequent separation and recovery as a final gasoline product and gas, together with similar materials from the fractionating zone of the coking stage. 45

Following are the results obtained from the operation above described: Approximately 69 percent of gasoline having the following analysis was recovered, based on the total charging stock (topped crude and pressure distillate) supplied 50 to the system:

A. P. I. gravity	61°
Initial boiling point	F. 88°
End boiling point	F. 390°
Antiknock value (motor method)	69 55
Vapor pressure (Reid)	lbs. per sq. in. 9

The coke produced amounted to approximately 37 pounds per barrel of charging stock and was of a quality readily marketable as domestic fuel. 60

The uncondensable gas produced amounted to approximately 385 cubic feet per barrel of charging stock and when subjected to absorption additional yields of high antiknock gasoline fractions may be recovered therefrom. 65

The only other products recovered from the system in the operation above described were approximately 12 percent, based on the total charging stock, of two grades of good quality fuel, one of which, comprising heavy fuel, was recovered as a portion of the residual liquid from the primary vaporizing and reparation chamber and having an A. P. I. gravity of approximately 42° and a viscosity of approximately 60 seconds (Saybolt Furol) at 122° F. The other, comprising light 70 75

fuel, was recovered as condensate resulting from passing vaporous products from coking chambers in operation through coking chambers about to be placed in operation in order to heat and precondition the latter. This product has a gravity of approximately 21° A. P. I. and an end boiling point of approximately 640° F.

I claim as my invention:

1. In a process for the selective cracking of relatively low-boiling and high-boiling hydrocarbon oils wherein separate streams of hydrocarbon oils of different boiling range characteristics are each subjected to conversion conditions of cracking temperature and superatmospheric pressure in separately controlled cracking zones, the resultant heated products commingled and subjected to appreciable continued cracking time at the attained temperature of the mixture and at substantial superatmospheric pressure, the resultant conversion products supplied in commingled state to a zone of substantially reduced pressure wherein their vaporous and liquid components separate, the vapors subjected to fractionation whereby their components boiling above the desired temperature are condensed as reflux condensate and separated into selected low-boiling and higher boiling fractions which are supplied, respectively, to the relatively light oil and relatively heavy oil cracking steps, the improvement which comprises subjecting fractionated vapors of the desired end-boiling point from the aforementioned fractionating step to further fractionation whereby to separate the same into gasoline vapors of the desired end-boiling point and satisfactory antiknock value and a higher boiling condensate including high-boiling gasoline fractions of unsatisfactory antiknock value, subjecting said desired gasoline vapors to condensation, recovering the resulting distillate, subjecting said higher-boiling condensate to reforming conditions of cracking temperature and substantial superatmospheric pressure in another independently controlled cracking zone, introducing regulated quantities of the highly heated products from the last mentioned cracking zone into a coking zone to which heated residual products of the process are supplied as hereinafter described and wherein the latter are reduced to coke, supplying vaporous products from the coking zone to another low pressure separating zone, removing from said zone of substantially reduced pressure said liquid components separated from the vaporous components of the commingled conversion products supplied thereto, introducing said liquid conversion products into the low pressure separating zone to which said vaporous products from the coking zone are supplied, removing the resultant non-vaporous residual liquid from said low pressure separating zone, quickly heating the same in another separately controlled cracking zone to a temperature sufficient to induce subsequent coking of the residual liquid, introducing the heated products from the last mentioned cracking zone into the coking zone wherein their high-boiling components are reduced to substantially dry coke, subjecting vaporous products from said low pressure separating zone to fractionation for the formation of reflux condensate, supplying the reflux condensate from the last mentioned fractionating zone to the first mentioned fractionating zone, subjecting fractionated vapors of the desired end-boiling point and comprising materials within the boiling range 75 of gasoline from said last mentioned fractionating zone to condensation, and recovering the resulting distillate.
2. In a process for the selective cracking of relatively low-boiling and high-boiling hydrocarbon oils wherein separate streams of hydrocarbon oils of different boiling range characteristics are each subjected to conversion conditions of cracking temperature and superatmospheric pressure in separately controlled cracking zones, the resultant heated products commingled and subjected to appreciable continued cracking time at the attained temperature of the mixture and at substantial superatmospheric pressure, the resultant conversion products supplied in commingled state to a zone of substantially reduced pressure wherein their vaporous and liquid components separate, the vapors subjected to fractionation whereby their components boiling above the desired temperature are condensed as reflux condensate and separated into selected low-boiling and higher boiling fractions which are supplied, respectively, to the relatively light oil and relatively heavy oil cracking steps, non-vaporous residual liquid supplied in regulated quantities from said zone of reduced pressure to another separate cracking zone wherein it is quickly heated to an independently controlled cracking temperature and the heated products introduced into a coking zone wherein their high-boiling components are reduced to coke, the improvement which comprises removing vaporous products from the coking zone, supplying the same to another separating zone wherein high-boiling components undesirable as cracking stock for either of the first mentioned selective cracking stages are removed therefrom, removing said high-boiling components in liquid state from the last mentioned separating zone and supplying the latter to the same cracking zone to which said residual liquid is supplied, subjecting vaporous products of the coking operation from the last mentioned separating zone to separate fractionation for the formation of reflux condensate, returning the last mentioned reflux condensate in regulated quantities to the first mentioned fractionating zone, subjecting fractionated vapors of the desired end-boiling point from said separate fractionating zone to condensation, recovering the resulting distillate, subjecting fractionated vapors of the desired end-boiling point from the first mentioned fractionating zone to further fractionation whereby they are separated into gasoline vapors of the desired end-boiling point and higher boiling condensate including heavy gasoline fractions of unsatisfactory antiknock value, subjecting said gasoline vapors of the desired end-boiling point to condensation, recovering the resulting distillate, subjecting said condensate including unsatisfactory gasoline fractions to reforming conditions of high cracking temperature and substantial superatmospheric pressure in another independently controlled cracking zone, introducing regulated quantities of the highly heated products from the last mentioned cracking zone into the coking zone to assist the coking operation, cooling the remaining portion of said highly heated products sufficiently to prevent their substantial further cracking, separating heavy liquid components from the partially cooled materials, returning said heavy liquids to the same cracking zone to which said residual liquid is supplied, subjecting vaporous components of the partially cooled materials to fractionation for the formation of reflux condensate and the recovery of fractionated vapors of the desired end- 75

boiling point which are condensed and collected, and returning the last mentioned reflux condensate in regulated quantities to the first mentioned fractionating zone.

5. 3. A process such as defined in claim 1 wherein at least a portion of said condensate supplied to the reforming stage of the system is first passed in indirect heat exchange with reflux condensate formed in the fractionating zone to which the vaporous products of the coking operation are supplied, prior to the return of said reflux condensate to the first mentioned fractionating zone.

4. A process such as defined in claim 2 wherein at least a portion of said condensate supplied to the reforming stage of the system is first passed in indirect heat exchange with reflux condensate formed in the fractionating zone to which the vaporous products of the coking operation are supplied, prior to the return of said reflux condensate to the first mentioned fractionating zone.

5. In a process wherein hydrocarbon oils are cracked at elevated temperature and superatmospheric pressure, the resulting vaporous and liquid conversion products separated, the vapor fractionated to form reflux condensate which is returned to said cracking operation for further cracking and said liquid products appreciably further vaporized at substantially reduced pressure relative to that employed in the cracking zone whereby additional vapors are formed, the improvement which comprises removing resultant non-vaporous liquid residue from the zone wherein said further vaporization of the liquid conversion products is accomplished and reducing its high-boiling components to coke in a coking zone, separating high-boiling components from the vaporous products of the coking operation and returning the same to the coking zone for further treatment, recovering fractions boiling within the range of the desired gasoline product from the remaining vaporous products of the coking operation, condensing intermediate fractions of the vaporous products of the coking operation and returning the same to the aforementioned cracking operation for further cracking, said additional vapors being fractionated together with said remaining vaporous products of the coking operation whereby condensed portions of the additional vapors are also returned to the cracking operation, further fractionating the vaporous products from which said reflux condensate has been recovered to separate therefrom desirable gasoline fractions of satisfactory anti-knock value, which are condensed and recovered, and to form a higher boiling condensate comprising heavy gasoline fractions of unsatisfactory anti-knock value, subjecting said higher boiling condensate in a separate cracking zone to independently controlled cracking conditions of elevated temperature and superatmospheric pressure adequate to materially improve the anti-knock value of said heavy gasoline fractions, recovering good anti-knock gasoline from the vaporous products of the last mentioned cracking operation, separating the remainder of the last named conversion products into light and heavy liquid fractions, returning the latter to the coking zone for further treatment and returning the former to the first mentioned cracking operation for further cracking.

6. A process such as defined in claim 5 wherein the first mentioned cracking operation comprises two independently controlled cracking steps to

which are selectively supplied relatively low-boiling and higher boiling fractions of said reflux condensate.

7. A process such as defined in claim 5 wherein in said fractionation of the first mentioned vaporous products is accomplished in commingled state with hydrocarbon oil charging stock for the process, the resulting reflux condensate being separated into selected relatively low-boiling and higher boiling fractions, each of which contain selected fractions of said charging stock, and wherein the first mentioned cracking operation comprises independently controlled cracking steps to which said low-boiling and higher boiling fractions of the reflux condensate are selectively supplied.

8. A process such as defined in claim 5 wherein in non-vaporous liquid residue resulting from initial further vaporization of the liquid products of the first mentioned cracking operation is introduced, prior to said coking thereof, into a zone of secondary further vaporization to which said vaporous products of the coking operation are supplied and wherein said separation of high-boiling components from the latter is accomplished, the liquid residue from said zone of secondary further vaporization being supplied to the coking zone.

9. A process such as defined in claim 5 wherein in non-vaporous liquid residue resulting from initial further vaporization of the liquid products of the first mentioned cracking operation is introduced, prior to said coking thereof, into a zone of secondary further vaporization to which said vaporous products of the coking operation are supplied and wherein said separation of high-boiling components from the latter is accomplished, resultant liquid residue being removed from said zone of secondary further vaporization, quickly heated to a higher cracking temperature in an independently controlled heating zone of the system and the resulting highly heated products introduced into said coking zone wherein their high-boiling components are reduced to coke.

10. A process such as defined in claim 5 wherein in the first mentioned cracking operation comprises two independently controlled cracking steps to which selected relatively low-boiling and higher boiling fractions of said reflux condensate are selectively supplied and wherein regulated quantities of the highly heated products from the cracking step to which said relatively low-boiling fractions of the reflux condensate are supplied, are introduced into the coking zone wherein they serve as a heating medium for assisting coking of said liquid residue.

11. A process such as defined in claim 5 wherein in said condensed intermediate fractions of the vaporous products of the coking operation are returned to the fractionating step to which said vaporous products of the first mentioned cracking operation are supplied, reflux condensate resulting from said fractionation of the commingled materials being separated into selected relatively low-boiling and higher boiling fractions which are selectively supplied to independently controlled light oil and relatively heavy oil cracking steps of the first mentioned cracking operation.

12. A process such as defined in claim 5 wherein in said light liquid fractions separated from said remaining conversion products of the last mentioned cracking operation are commingled with said vaporous products of the first mentioned

- cracking operation in the zone wherein the latter are fractionated, and wherein reflux condensate resulting from fractionation of the commingled materials is separated into selected relatively low-boiling and higher boiling fractions which are selectively supplied to independently controlled relatively light oil and relatively heavy oil cracking steps of the first mentioned cracking operation.
13. In a process wherein hydrocarbon oils are cracked at elevated temperature and superatmospheric pressure, the resulting vaporous and liquid conversion products separated, the vapors fractionated to form reflux condensate which is returned to said cracking operation for further cracking and said liquid products appreciably further vaporized at substantially reduced pressure relative to that employed in the cracking zone whereby additional vapors are formed, the improvement which comprises removing resultant non-vaporous liquid residue from the zone wherein said further vaporization of the liquid conversion products is accomplished and reducing its high-boiling components to coke in a coking zone, separating high-boiling components from the vaporous products of the coking operation and returning the same to the coking zone for further treatment, fractionating the remaining vaporous products of the coking operation in admixture with said additional vapors but out of contact with the aforementioned vapors of the cracking operation to form a separate reflux condensate, returning the latter to the first mentioned fractionating step and separately recovering gasoline fractions from the fractionated vapors of each of said fractionating steps, the process being further characterized in that said cracking operation comprises two independently controlled cracking steps to which selected relatively low-boiling and higher boiling fractions of the reflux condensate from the first mentioned fractionating steps are selectively supplied and in that regulated quantities of the highly heated products from the cracking step to which said relatively low-boiling fractions are supplied, are introduced into the coking zone wherein they serve as a heating medium for assisting coking of said liquid residue.
14. A process such as defined in claim 13 wherein non-vaporous liquid residue resulting from initial further vaporization of the liquid products of said cracking operation are introduced, prior to said coking thereof, into a zone of secondary further vaporization to which said vaporous products of the coking operation are supplied and wherein said separation of high-boiling components from the latter is accomplished, the liquid residue from said zone of secondary further vaporization being supplied to the coking zone.
15. A process such as defined in claim 13 wherein non-vaporous liquid residue resulting from initial further vaporization of the liquid products of said cracking operation are introduced, prior to said coking thereof, into a zone of secondary further vaporization to which said vaporous products of the coking operation are supplied and wherein said separation of high-boiling components from the latter is accomplished, resultant liquid residue being removed

from said zone of secondary further vaporization, quickly heated to a high cracking temperature in an independently controlled heating zone of the system and the resulting highly heated products introduced into said coking zone wherein their high-boiling components are reduced to coke.

16. In a process wherein hydrocarbon oils are cracked at elevated temperature and superatmospheric pressure, the resulting vaporous and liquid conversion products separated, and the vapors fractionated to form reflux condensate which is returned to said cracking operation for further cracking, the improvement which comprises further fractionating the vaporous products from which said reflux condensate has been recovered to separate therefrom desirable gasoline fractions of satisfactory anti-knock value, which are condensed and recovered, and to form a higher boiling condensate comprising heavy gasoline fractions of unsatisfactory anti-knock value, heating said higher boiling condensate in a separate cracking zone to independently controlled cracking conditions of elevated temperature and superatmospheric pressure adequate to materially improve the anti-knock value of said heavy gasoline fractions, effecting appreciable further vaporization of said liquid products of the first mentioned cracking operation in a zone of substantially reduced pressure relative to that wherein they are formed, introducing resulting non-vaporous liquid residue and products of the last mentioned cracking operation into another vaporizing and separating zone wherein further vaporization of said liquid residue is accomplished and wherein vaporous and high-boiling liquid fractions of said last mentioned conversion products are separated, separately removing the resulting non-vaporous residual liquid products and vapors from the last mentioned vaporizing and separating zone and fractionating the vapors to separate therefrom desirable gasoline fractions which are condensed and recovered, the process being further characterized in that the first mentioned cracking operation comprises two independently controlled cracking steps to which are selectively supplied relatively low-boiling and higher boiling fractions of the reflux condensate formed in the first mentioned fractionating step and in that reflux condensate resulting from said fractionation of the last named vapors is also separated into selected relatively low-boiling and higher boiling fractions which are selectively returned for further cracking to said independently controlled cracking steps of the first mentioned cracking operation.

17. A process such as defined in claim 16 wherein said fractionation of the first mentioned vaporous products is accomplished in commingled state with charging stock comprising hydrocarbon oil boiling above the range of gasoline, the resulting reflux condensate being separated into selected relatively low-boiling and higher boiling fractions, each of which contain selected fractions of said charging stock, and wherein the first mentioned cracking operation comprises independently controlled cracking steps to which said low-boiling and high-boiling fractions of the reflux condensate are selectively supplied.
